(57) **CLAIM**

The ornamental design for a box seat, as shown and described.

DESCRIPTION

FIG. 1 is a front elevational view of the box seat showing my new design;

FIG. 2 is a side elevational view of the box seat, the opposite side elevational view being a mirror image of the side shown;

FIG. 3 is a rear elevational view

FIG. 4 is a perspective view viewed from an upper right front position;

FIG. 5 is perspective view viewed from the bottom right position; and,

FIG. 6 is a cross-sectional view taken along line 6—6 in FIG. 1.
